UNITED STATES PATENT OFFICE.

WILLIAM A. COLLINGS, OF KANSAS CITY, MISSOURI.

DEFORMED REINFORCING-BAR.

1,152,606.

Specification of Letters Patent.

Patented Sept. 7, 1915.

Application filed February 24, 1914. Serial No. 820,457.

To all whom it may concern:

Be it known that I, WILLIAM A. COLLINGS, a citizen of the United States, and a resident of the city of Kansas City, in the State of Missouri, have invented certain new and useful Improvements in Deformed Reinforcing-Bars; and I do hereby declare that the following is a full, clear, and exact description of the same, reference being had 10 to the accompanying drawings, and to the numerals of reference marked thereon, which form a part of this specification.

It is a well known fact that although concrete acts admirably under compression, that 15 it is very liable to fail under tension. Accordingly, the concrete is usually reinforced by steel reinforcing members disposed below the neutral axis in a beam or the like, so that said members receive the tension to 20 which the lower layers of concrete are subjected. It has been found, however, that even with reinforcing members, a beam is liable to failure, owing to the fact that reinforcing elements which are improperly 25 formed may slip in the concrete and may even, due to their configuration, promote a cracking thereof, which is, of course, dangerous and undesirable.

This invention relates to a steel reinforcing bar which has integrally formed thereon 30 helically disposed rounded ribs staggered relative one another along the length of the bar.

The bar disclosed in my invention is readily formed between rolls for the purpose and 35 does not necessitate a construction involving complicated manipulations of the bar through an intricate number of rolls of various configuration, but only requires the use 40 of simple types of rolls, permitting easy and cheap manufacture of the bar.

It is an object of this invention to provide a reinforcing bar of circular cross section, though not necessarily so, and with 45 ribs integrally formed on portions of the periphery thereof and in offset relation with one another.

It is also an object of this invention to construct a device adapted to effectively 50 bond in the concrete, and affording rounded surfaces at the points of contact therewith except at the extreme ends of the deforming elements formed on the bar.

It is further an object of this invention to 55 construct a reinforcing bar wherein ribs are helically disposed on the periphery thereof

with an end of each of said ribs affording a flat contact surface to bond in the concrete to insure a fixed position of the bar therein and to prevent rotation thereof even in 60 slight amounts.

It is finally an object of this invention to construct a reinforcing bar having ribs helically disposed thereon so as to prevent sliding or rotational movement of said bar in 65 the concrete.

The invention (in a preferred form) is hereinafter more fully defined and described in the accompanying drawings and specification.

In the drawings: Figure 1 is a top plan view of a portion of a reinforcing bar with the ribs shown diagrammatically or straight thereon. Fig. 2 is a side elevation of a portion of a bar showing the ribs in their true 75 helical position upon the bar. Fig. 3 is a section on line 3-3 of Fig. 2. Fig. 4 is a fragmentary section on line 4-4 of Fig. 3.

As shown in the drawings: The bar itself, which is conventionally shown as of circular cross section, is denoted by the reference numeral 1, and during the process of rolling the same is formed with the various helically disposed ribs 2, and 3, respectively on its periphery. It is to be noted that each of said 80 ribs has a flat surface 4, forming the termination of one end thereon and that said flat surfaces are in line with one another longitudinally of the bar and substantially at right angles to the surface thereof. As 85 already stated, it has been found very difficult to roll certain reinforcing bars for the reason that the design of the same has often been such, that the ribs formed thereon have precluded a simple rolling operation. How- 90 ever, the line of termination of the flat surfaces of the ends of the ribs formed on the bar in my invention represents the parting line of the rolls, and it is readily evident that 95 the forming or rolling operation is not only practical, but exceedingly simple to perform, thus cheapening the cost of manufacture of the device. It is to be further noted that the ribs 2, extend for substantially a quarter 100 of the circumference around the bar, and are helically in line with one another.

The ribs 3, are semi-circumferential with respect to the bar and, of course, are helically disposed thereon. The adjacent ends of the respective ribs 2, terminate in a 110 rounded contour as denoted by the reference numeral 5, so that thus a rib is afforded hav-

ing one end flat and substantially perpendicular to the surface of the bar; and the other end tapered and rounded off relative thereto. The rounded ends 5, on certain of the ribs, afford a smooth and easily bonded surface on the bar, while the helical disposition of the ribs prevent a rotation of the bar when embedded in the concrete and the same are further prevented from rotation 10 by the flat abutting surfaces 4.

I am aware that various details of construction may be varied through a wide range without departing from the principles of this invention. I therefore do not pur- 15 pose limiting the patent otherwise than necessitated by the prior art.

I claim as my invention:
In a device of the class described, a bar,

and a plurality of groups of helically ar- 20 ranged long and short ribs integral therewith on the periphery thereof, each of said ribs having one end terminating in a broad flat abutting face, said faces of the respective ribs being all in substantially the same plane longitudinally of the bar, and said 25 short ribs having their adjacent ends in alinement with each other and being rounded and tapering.

In testimony whereof I have hereunto subscribed my name in the presence of two 30 subscribing witnesses.

WILLIAM A. COLLINGS.
